UNITED STATES PATENT OFFICE.

SHUBAEL COTTLE, OF NEW YORK, N. Y.

DESIGN FOR JEWELRY-BASES.

Specification forming part of Design No. 7,254, dated March 24, 1874; application filed January 17, 1874.
[Term of Patent 3½ years.]

To all whom it may concern:

Be it known that I, SHUBAEL COTTLE, of New York city, county, and State, have invented a new and Improved Design for Jewelry-Bases; and I do hereby declare that the following is a full, clear, and exact description of the same, reference being had to the accompanying drawings forming a part of this specification, in which—

Figures 1, 2, and 3 are views illustrating my design.

My invention consists in a new design, as hereinafter described, for the bases of buttons, studs, pins, ear-rings, scarf-pins, lockets, and other articles of jewelry.

A is the center, surrounded with a rim or

bissel, B, which is itself surrounded with a row of gold shot, C. The shot C are surrounded with a wide border, D, which constitutes the peculiar feature of my design.

Heretofore the row of shot has been surrounded with a sharp border in the shape of an inverted V.

Having thus described my invention, what I claim is—

The design shown and described, for jewelry-bases, formed by a wide, flat border, D, about the row of shot C.

SHUBAEL COTTLE.
